ELEMIR J. NEY, OF LOWELL, MASSACHUSETTS,

ASSIGNOR TO THE LOWELL MANUFACTURING COMPANY.

Letters Patent for a Design No. 80, dated July 16, 1861.

SPECIFICATION.

TO ALL WHOM IT MAY CONCERN:

Be it known, that I, ELEMIR J. NEY, of Lowell, in the county of Middlesex and State of Massachusetts, have originated and designed a new Pattern for Carpets or other fabrics; of which the following is a full, clear, and exact description, reference being had to the accompanying drawings making part of this specification.

Corner A is one-fourth of a large rosette, surrounded by sprigs, and resting on a ground B, surrounded by the scalloped band 1. The lace work 2 surrounds the whole figure, composed of the rosette, sprigs, ground, and band, before mentioned. Corner C is one-fourth of a small rosette resting on a ground 3.

The large wreath E E also rests on the ground 3.

Outside of the wreath E E small leaves radiate from the ground 3. F, at side, is a ground composed of diamonds and crosses, and surrounded by a wreath leaves 4. The remainder of the design is occupied by the sprigs 5 and 6.

The colors employed for the different portions of the design may be varied to suit the taste and wish of the manufacturer.

Claim.

What I claim as my invention, and desire to secure by Letters Patent, is—
The design or pattern for carpets or other fabrics herein set forth.
